TOY FOR BALANCING AND WALKING

Harold Katz, University City, Mo., assignor to
Harry Shear, St. Louis, Mo.

Filed June 27, 1960, Ser. No. 61,120

Term of patent 14 years

(Cl. D34—5)

FIG. 1.

FIG. 2.

Figure 1 is a perspective view partly from below of a toy for balancing and walking embodying my new design.

Figure 2 is a top plan view thereof.

I claim:

The ornamental design for a toy for balancing and walking, substantially as shown.
